Specification of Letters Patent. Patented May 27, 1919.

Application filed April 26, 1915, Serial No. 24,053. Renewed August 17, 1917. Serial No. 186,826.

To all whom it may concern:

Be it known that we, CONRAD REGENBOGEN and HANS TECHEL, citizens of the German Empire, residing at Kiel-Gaarden, Germany, and Kiel, Germany, have invented 5 certain new and useful Improvements in Submarine Boats, of which the following is a specification.

The present invention relates to submarine 10 boats which are driven on the surface by steam engines.

In the accompanying drawing, one embodiment of the invention is illustrated, showing a vertical cross section through the 15 boiler chamber of a submarine boat of this kind.

A is the pressure proof inner vessel, B the thin walled outer housing, and C the upper structure in the shape of a platform which 20 may be flooded. In the boiler chamber D is a water-tube boiler E, supported on a platform secured in the pressure proof inner vessel A, this boiler being constructed for oil fuel, the casing e^1 of which is connected to 25 a smoke-stack, which runs through the pressure proof inner vessel, the casing e^1 , however, not coming in direct contact with this inner vessel. The smoke-stack is composed of a stationary lower part F and an upper 30 part F^1 , which may be felled down about a hinge f^2 during submarine travel.

The lower part F of the smoke-stack, which may be closed water-tight in known manner by a lid (not shown) during submarine 35 travel, has double walls, the hollow chamber between them being connected through inlet and outlet piping G and H for cooling water. A pump K drives the cooling water through said hollow chamber 40 in the direction of arrows α and γ .

The cooled part F of the smoke-stack is extended a little into the pressure proof inner vessel A of the boat, so that the heat of the boiler casing e^1 connected thereto, 45 cannot be directly transmitted to the pressure proof inner vessel.

The advantage of the described device then obviously resides therein that a uniform temperature will be maintained in 50 that part of the smoke-stack which reaches down into the pressure proof inner vessel A and which would become very hot during operation without the cooling and be suddenly very much cooled upon the flooding

of the upper structure C. As a consequence, a tight joint around this portion of the smoke-stack is now obtained. 55

The preservation of this tight joint between the smoke-stack and the pressure proof inner vessel, is still more favored 60 thereby that no great amount of heat from the boiler casing e^1 is transmitted directly to the pressure proof inner vessel, but is instead transmitted to the downward extension of part F of the smoke-stack and from 65 there to the cooling water.

We claim:

1. In a submarine boat having a steam boiler inclosed in a pressure proof inner vessel, a smoke-stack for the boiler, said 70 smoke-stack being provided with double walls forming a cooling chamber extending into said vessel, and conduits for said chamber for circulating cooling medium in said chamber. 75

2. In a submarine boat having a steam boiler inclosed in a pressure proof inner vessel and supported by said vessel, a casing surrounding the boiler, said casing being suspended in such a manner that it does not 80 come in direct contact with the walls of said vessel.

3. In a submarine boat having a steam boiler inclosed in a pressure proof inner vessel and supported by said vessel, a casing 85 surrounding the boiler, a smoke-stack for the boiler, said smoke-stack penetrating said vessel and being provided with a downwardly projecting portion extending into said vessel and from which said casing is 90 suspended in such a manner that it does not come in direct contact with the walls of said vessel.

4. In a submarine boat having a steam boiler inclosed in a pressure proof inner vessel and supported by said vessel, a casing surrounding the boiler, a smoke-stack for the boiler, said smoke-stack penetrating said vessel and being provided with a downwardly projecting portion extending into 100 said vessel and from which said casing is suspended in such a manner that it does not come in direct contact with the walls of said vessel; said downwardly projecting portion having double walls forming a cooling chamber, and conduits for said chamber for circulating cooling medium in said chamber. 105

5. In a submarine boat having a steam

- boiler inclosed in a pressure proof inner vessel and supported by said vessel, a smoke-stack for the boiler, said smoke-stack penetrating said vessel and being provided with
5 a downwardly projecting portion extending into said vessel, a casing surrounding the boiler so dimensioned and suspended from the said downwardly projecting portion of the smoke stack that the casing does not
10 come in direct contact with the walls of said vessel; said smoke-stack being secured by tight joints to said casing as well as to said vessel and the outer walls of the boat.
6. In a submarine boat having a steam

boiler inclosing in a pressure proof inner vessel, a smoke stack for said boiler, said smoke stack having a cooling chamber extending into said vessel, and means for circulating a cooling medium in said chamber.

In testimony whereof the foregoing specification is signed in the presence of two witnesses.

CONRAD REGENBOGEN.
HANS TECHEL.
